LIGHTNING DEMONSTRATOR

Sidney D. Kretzer, St. Louis, Mo.

Application March 11, 1953, Serial No. 23,985

Term of patent 7 years

(Cl. D25—1)

To all whom it may concern:

Be it known that I, Sidney D. Kretzer, a citizen of the United States, residing in St. Louis, State of Missouri, have invented a new, original, and ornamental Design for a Lightning Demonstrator, of which the following is a specification, reference being had to the accompanying drawing, forming a part thereof.

Fig. 1 is a top plan view of a lightning demonstrator, showing my new design;

Fig. 2 is a side elevational view thereof; and

Fig. 3 is an end elevational view thereof.

The dominant features of my new design are shown in solid lines in the drawing.

I claim:

The ornamental design for a lightning demonstrator, substantially as shown and described.

SIDNEY D. KRETZER.
